UNITED STATES PATENT OFFICE

2,418,917

ELECTROTHERAPY

Fred Weinman, Brooks, Oreg.

Application October 18, 1944, Serial No. 559,199

2 Claims. (Cl. 128—406)

1

This invention relates to therapeutic devices.

An object of this invention is to provide an electrically operated device which is adapted for treatment of various physical ailments.

Another object of this invention is to provide a therapeutic device wherein electric shock may be combined with heat produced from electricity for treatment of numerous ailments such as rheumatism or the like.

A further object of this invention is to provide a therapeutic device of this kind which includes an improved means for regulating the amount of electric current delivered by the device.

With the foregoing and other objects in view, the invention will be more fully described hereinafter, and will be more particularly pointed out in the claims appended hereto.

In the drawings wherein like symbols refer to like or corresponding parts throughout the several views,

Figure 1 is a plan view of a therapeutic device constructed according to an embodiment of this invention.

Figure 1^a is a diagrammatic view of an attachment for use with this invention.

Figure 2 is a sectional view taken on the line 2—2 of Figure 1.

Figure 2^a is a detailed side elevation of one of the foot contacts removed from the device.

Figure 3 is a sectional view taken on the line 3—3 of Figure 1.

Figure 4 is a diagrammatic view showing the electric circuits embodied in this invention.

Referring to the drawings, the numeral 10 designates generally a base which may be constructed of wood or other suitable material and which has secured to the lower side thereof a plurality of supporting feet 13. The base 10 is formed with an inclined upper surface 11 extending inwardly and upwardly from one end thereof and a pair of contact plates 12 and 12^a are secured to the inclined surface 11 by fastening members 14 and 15, respectively.

The plate 12 at its outer or forward end is formed with a barrel 16 and the plate 12^a at its outer or forward end is formed with a barrel 17. A wire 18 is secured in the barrel 16 of plate 12, and a wire 19 is secured in barrel 17. The two wires 18 and 19 are secured to an outlet socket 20 which is secured by suitable fastening means to the forward end of the base 10 below the contact plates 12 and 12^a. Plate 12 at the inner end is formed with a depending extension 21 which extends downwardly into a recess or

2

reservoir 22 formed in the base 10 at the rear ends of the plates 12 and 12^a.

The vertical extension 21 is also formed with a horizontal extension 23 and one end of a swingable circuit regulating member 24 is pivotally secured as at 25 to the horizontal extension 23. The regulating member 24 is of serpentine configuration and at its free end is provided with an upwardly extending arm 26, and the latter has a horizontal extension 27 on which an insulating knob 28 is secured. The extension 27 overlies the upper side of the base 10 and the adjacent end of the reservoir 22 is provided with graduations 29 which are correlated with the extension 27 so that the user of this device can regulate the amount of electric current which is being passed to contact plates 12 and 12^a. Plate 12^a as shown in Figure 2^a is formed with a vertical depending extension 30 extending into the reservoir 22, and a terminal 31 is secured to the lower portion of the extension 30.

The reservoir 22 is adapted to have water 32 mounted therein, the water providing a resistance element and at the same time a conductor which connects the inner ends of the contact plates 12 and 12^a together. The bottom wall 33 of the reservoir 22 is provided with an opening 34 which is normally closed by a tapered plug 35 so that the water may be drained from the reservoir 22 as may be desired. The contact plate 12^a as shown in Figure 4 has connected therewith one end of a wire 36 and this wire at the opposite end is adapted to be connected to a source of electric current supply. A second wire 37 is connected at one end to the supply source and at the other end is connected to a socket 38 secured to the upper side of the base 10 adjacent the rear thereof.

A high resistance light bulb 39 is mounted in the socket 38 and is adapted when lighted to provide the necessary resistance in conjunction with the water 32 for regulating the amount of current discharged from contact plates 12 and 12^a. A wire 40 is connected to the opposite side of the light socket 38 and is connected to a wire 41, the latter being connected to terminal 31. A manually operable switch 42 is interposed in wire 40 so that electric current may selectively be passed through light bulb 39 to wire 41 and terminal 31.

A second light bulb socket 43 is connected by means of a wire 44 to a wire 45 with the latter wire connected to wire 37. A wire 46 connects socket 43 to wire 41 and a switch 47 is interposed in wire 46. A third socket 48 is mounted on the base 10 and is connected by a wire 49 to wire 45.

A wire 50 connects socket 48 with wire 41 and a switch 51 is interposed in wire 50. A high resistance light bulb 52 is mounted in socket 43 and a high resistance light bulb 53 is mounted in socket 48.

In order to provide a means whereby electric current from the contact plates 12 and 12^a may be extended to the hands of the user, I have provided a pair of hand gripping members 54 and 55. The member 55 is connected by means of a wire 56 to one side of a plug connector 57 and hand gripping member 55 is connected by means of a wire 58 to the other side of connector 57. Connector 57 is adapted to be engaged with connector socket 20. Base 10 has extending from one side thereof a U-shaped handle 59 which has the opposite parallel sides thereof sunk or embedded within the base 10. A handle 59 provides a convenient means whereby the base 10 may be readily shifted to the desired point for engagement with the source of electric current supply.

Reservoir 22 is normally closed by means of a closure 60 which is pivotally secured at its rear end as at 61 to the base 10, and a pivoted locking member 62 which is positioned between the contact plates 12 and 12^a is adapted to engage the forward end of closure 60 so as to hold the latter in closed position over the reservoir 22.

In the use and operation of this device, wires 36 and 37 are connected to a source of electric current supply and reservoir 22 is substantially filled with water. Switch 42 may be closed so as to light the light bulb 39 and thereby provide one degree of resistance to plate 12^a. When regulating member 24 is moved rearwardly or away from the rear end of contact plate 12^a, the water in reservoir 22 will provide the maximum resistance between plates 12 and 12^a. If it is desired to increase the electric current, knob 28 is moved forwardly, thereby swinging regulating member 24 closer to contact plate 12^a and reducing the resistance of the water to the electric current passing from regulating member 24 to terminal 34. The user of the device is adapted to place one foot on each of plates 12 and 12^a so that the electric current will pass into the body through the

feet. If it is desired to also have the electric current pass through the hands and arms of the user, connector 57 is engaged with socket 20 and the hand gripping members 54 and 55 are positioned in the hands of the user.

What is claimed is:

1. An electrical device comprising a base, a pair of spaced contact plates mounted on said base in spaced apart parallel relation and inclined to the horizontal, a liquid reservoir formed in said base, extensions carried by said plates engaging within said reservoir, a regulating member disposed within said reservoir and pivotally carried at one end by one of said extensions, said regulating member being swingable toward or away from the other of said extensions to thereby vary the resistance of the liquid in said reservoir, a non-conducting cover over said reservoir, and means connecting said plates with a source of electric current supply.

2. An electrical device as set forth in claim 1 including a plurality of selective illuminable resistance members carried by said base and interposed in said connecting means.
